UNITED STATES PATENT OFFICE.

PAUL FRIEDRICH SCHALLER AND CHARLES SUNDT, OF PARIS, FRANCE.

SMOKE-CONSUMER.

1,070,185.

Specification of Letters Patent. Patented Aug. 12, 1913.

Application filed September 18, 1911. Serial No. 650,006.

To all whom it may concern:

Be it known that we, PAUL FRIEDRICH SCHALLER, subject of the German Emperor, and CHARLES SUNDT, a subject of the King 5 of Norway, residing at 110 Rue Réaumur, Paris, France, have invented certain new and useful Improvements in Smoke-Consumers, of which the following is a specification, reference being had therein to the 10 accompanying drawing.

This invention relates primarily to the combustion of fuel, has especial reference to smoke consumers, has for its object economy in the consumption of fuel and the avoidance 15 of smoke, soot, gases or other unconsumed products of combustion being emitted from smoke stacks, chimneys and the like.

The invention consists in certain improvements which will be fully disclosed in the 20 following specification and claim.

Many devices and methods have been proposed to produce combustion of gases and soot, or rather gases of distillation incompletely burned issuing from smoke stacks 25 and chimneys. To this end it has been proposed to heat air preferably in passages, hollow bodies or other structures. But in all these devices heretofore used, satisfactory results have not been obtained because 30 certain indispensable conditions have been neglected.

Practical experience has shown that perfect combustion of the gases in question cannot be obtained except under the conditions 35 that the air to support combustion is injected under pressure to the heated zone of the burning gases at a temperature higher than that of the gases.

This invention has for its purpose, a construction which will meet these indispensable conditions, and provides means placed in the hottest zone of the distilled gases escaping from an industrial, domestic or other furnace or fire place, said means comprising a hollow body of refractory material, such as iron, steel, clay, asbestos or the like which is exposed to said gases and heated to a very high degree of temperature.

The air taken from the outside and entering the hollow body, at the bottom or at the side is very highly heated, is discharged through small orifices or perforations made in the body on the side opposite to the orifice of admission. At the discharge orifice

of the hollow body, the air penetrates the 55 gases which have not been completely burned and assures the total combustion thereof, so that the stack or chimney allows only the non-combustible matter to escape, and the smoke or soot is consumed, or the amount 60 reduced to almost nothing. The heat of these gases being utilized before their escape from the chimney, the quantity of caloric being sensibly increased offers the 65 advantage of very great economy of combustion, which amounts to from fifteen to fifty per cent. To obtain this it is necessary that the hollow body be constructed so that the air passing through it is retarded in its circulation, so as to have time to be heated 70 to the temperature of the burning gases and to put it under pressure by its expansion. To obtain these results, the transverse total area of these many orifices of escape or discharge must be less than the area of the orifice or the orifices of admission in a proportion of about 1 to 2. The disposition of 75 walls or baffles with the passages alternate in dimensions, gradually getting larger, which form in the inside of the body a continuous passage, the free transverse area of 80 which becomes gradually larger according to the increase of the volume of air under the action of heat. The proportions of this gradual increase of the free transverse area 85 of this continuous passage formed in the interior of the hollow body must vary from 4:1 to 8:1, as compared with the orifice of admission in respect to the average temperature of industrial furnaces, stoves and 90 the like.

In the accompanying drawings, which form part of this specification:—Fig. 1 represents a vertical longitudinal section of one form of our invention. Fig. 2 is a vertical transverse section on line A—B, Fig. 1. Fig. 3 is a top plan view of the same. Fig. 4 is a vertical transverse section of a circular or modified form of construction. Fig. 5 is a like view of the same taken at a right 100 angle to Fig. 4. Fig. 6 is a vertical longitudinal section of a tubular boiler provided with a consumer of the construction shown in Fig. 1. Fig. 7 is a vertical transverse section on line 7—7, Fig. 6 on an enlarged 105 scale. Fig. 8 is a vertical longitudinal section through the furnace on line 8—8 Fig. 7. Fig. 9 is a vertical longitudinal section of a

boiler showing the application of the modified form of the consumer, and Fig. 10 is a vertical transverse section of the same.

Reference being had to the drawings and 5 the designating characters thereon, the consumer 1 shown in Figs. 1, 2 and 3 consists of a hollow body, rectangular in form, of metal or refractory material which can be made in one piece or composed of several 10 pieces, and is provided with an air inlet or supply opening 2 in the bottom thereof, baffle plates 3, and in the upper surface are discharge orifices or perforations 4. The air in its travel through the body 1, comes 15 in contact with the baffle plates 3, is retarded and becomes highly heated by the products of combustion produced by the ignition and distillation of the gases emanating from the fuel in the furnace. The area of the 20 passage through the body 1, is gradually increased, is continuous and effectually heats the air to a high degree of temperature. The area of the opening 2 is greatly 25 in excess of the combined area of the discharge orifices 4, so that the heated air is expanded and discharged at greater velocity than it is admitted and meets and thoroughly commingles with the gases and other products of combustion generated in the 30 furnace and produces thorough combustion of said gases and other products.

In the circular or modified form of consumer shown in Figs. 4 and 5, the opening 2 is placed in the center of the side opposite 35 that which is exposed to the flames or products of combustion from the furnace, and the discharge openings 4 are in the periphery, and between the supply and the discharge openings are arranged the baffle- 40 plates 3. The opening 2 in the several constructions and applications of the consumer may be provided with a conduit 5 for supplying exterior air to the consumer.

The number or applications of smoke- 45 consumers is naturally not exhausted by the samples of mounting shown in the drawings; the smoke-consumer can on the contrary be applied to industrial, domestic or other boilers, in adapting the mode of

mounting to the nature of the boilers. Also 50 the consumers may be made in other forms than those shown in the drawings.

Apparatus are known in which some baffles or walls compel the air to circulate or remain a certain length of time in the hollow body, but the free transverse sectional area of the passage has always been the same, and this is the reason why perfect combustion could not be obtained. Instead of penetrating under pressure into the flowing gases or mixing intimately therewith, the air simply followed the draft of the furnace or chimney and at the discharge it formed a parallel current with the gases formed in the furnace without mixing therewith to effect their total combustion. But the pressure that the air acquires in the present smoke-consumer can only be obtained by determining the dimensions to be given the orifices of supply and discharge, 70 and particularly to the gradually increasing dimensions of the passages in the interior of the hollow body.

Having thus fully described our invention, what we claim is:—

The combination of a furnace, a smoke consumer comprising a hollow body provided with a centrally disposed air supply, a plurality of discharge passages opposite the supply and whose combined area is less 80 than the area of the supply, and interposed baffle plates forming passages of increasing cross sectional area between said plates, and passages at the ends of the plates at approximately a right angle to the aforesaid 85 passages, whereby the air in its passage through the body is retarded, expanded and discharged under augmented pressure into the products of combustion proceeding from the furnace.

In testimony whereof we affix our signatures in the presence of two witnesses:

PAUL FRIEDRICH SCHALLER.
CHARLES SUNDT.
